UNITED STATES PATENT OFFICE.

CHARLES H. FESSLER, OF COVINGTON, PENNSYLVANIA.

SPRING-SUPPORTING CLAMP.

1,316,226.

Specification of Letters Patent. Patented Sept. 16, 1919.

Application filed January 8, 1919. Serial No. 270,178.

To all whom it may concern:

Be it known that I, CHARLES H. FESSLER, a citizen of the United States, residing at Covington, in the county of Tioga and State 5 of Pennsylvania, have invented certain new and useful Improvements in Spring-Supporting Clamps, of which the following is a specification, reference being had to the accompanying drawings.

10 This invention relates to spring supports and clamps, and particularly to a supporting clamp designed to engage the quarter elliptic springs used on certain well known makes of motor cars.

15 Springs of this character are attached to the longitudinal frame beams of these cars by bolts extending upward through the springs and engaging the flange of the frame beam and in about 80% of the breakages in

20 cars using these springs, the bolts break under the strain of service letting the ends of the springs drop.

25 The general object of my invention is to provide a device of the character described which will prevent this breakage and specifically to provide a device which will clamp the butt ends of the spring leaves together and which will also hold the butt end of the quarter elliptic springs supported firmly 30 against the spring bracket attached to the car frame.

35 A further object is to provide a device of this character so constructed that the clamp will take up 80% of the strain of the spring and permit a longer bolt to be used to take up the remaining 20% of the strain.

My invention is illustrated in the accompanying drawings, wherein:—

40 Figure 1 is a side elevation of a portion of an automobile frame and spring with my device applied, the axle being in section;

Fig. 2 is a vertical sectional view on the line 2—2 of Fig. 1; and

Fig. 3 is a top plan view of the clamp.

45 Referring to these drawings, it will be seen that my device comprises a spring support made of steel and approximately U-shaped in form, the support being designated 10 and the leg 12 of the support being longer 50 than the leg 11. The blank from which the support is made is approximately one-half inch thick. The leg 12 is formed with a relatively large screw-threaded opening 13 and passing through this opening is a tubular

55 screw 14 having exterior screw-threads engaging the screw-threads of the opening 13. This tubular screw is provided with a head 15 whereby a wrench may be applied. The opposite leg 11 is perforated for the passage 60 of a bolt 16 having a head at one end, the bolt passing through the several leaves of the elliptic spring and through the tubular screw 14 and head and being engaged by a nut 17.

65 The actual use of this device is illustrated in Fig. 1, wherein 18 designates the longitudinal frame beam of the car and 19 the usual bracket riveted or bolted thereto, this bracket having an outstanding flange perforated for the passage of the bolt 16. The 70 spring leaves which form the spring 20 are of any usual or suitable form and a spring is connected at its extremity to the axle 21. A bolt 22 may pass through the leaves and through the bracket 19 and the clamp 10 be 75 applied around the butt ends of the several leaves. The clamp, as illustrated in Fig. 2, has its leg 11 applied over the top of the bracket 19 and when it is in place the bolt 16 is passed through the leg 11, the bracket, 80 the spring leaves and the tubular screw 14 and then the nut 17 is applied. The screw 14 is rotated so as to force the spring leaves tightly together and hold them tightly 85 clamped before the nut 17 is turned up. Obviously two of these clamps 10 might be used with the spring 20 in place of using one of the clamps and the bolt 22.

90 With a construction of this character the screw 14 takes up 80% of the strain on the spring and holds the butt ends of the spring leaves abutted firmly against each other. Inasmuch as a relatively long bolt may be used, the bolt will be stronger and inasmuch 95 as very little strain comes upon this bolt, the bolt will not be liable to break.

I claim:—

1. A spring clamp of the character described, comprising an approximately U-shaped body adapted to embrace a supporting bracket and a plurality of spring leaves, and a tubular screw having screw-threaded engagement with one leg of the clamp, the other leg of the clamp being perforated for the passage of an attaching bolt. 100

105 2. The combination with a bracket and a plurality of spring leaves supported therefrom, the butt ends of the leaves being per-

forated, of a clamp therefor approximately U-shaped in form to provide two legs, one of which is adapted to rest upon the bracket and the other be disposed beneath the spring 5 leaves, a tubular screw passing through the latter leg and bearing against the spring leaves, and a bolt passing through both legs, the bracket, the spring leaves and the tubu-

lar screw and having a nut bearing against the end of the tubular screw. 10

In testimony whereof I hereunto affix my signature in the presence of two witnesses.

CHARLES H. FESSLER.
